TACKER AND STABILIZER THEREFOR

Stephen A. Crosby, Chicago, Ill.

Application February 17, 1940, Serial No. 319,380

11 Claims. (Cl. 1—49)

The invention relates to a functionally and structurally improved stapling machine and more particularly to a staple tacker. In staple tacking machines of the prior art, the driving impact imparted by the driver usually created an undesirable rebounding or recoiling action thus appreciably and disadvantageously reducing the ultimate effect of the desired blow or force against the driven staple. It is thus an important object of the present invention to materially overcome this disadvantage in positioning a concentrated laminated mass over the driver to absorb the recoil of the frame of the tacker and thereby effectively reduce undesirable rebounding of the frame at the instant of impact of the driven staple against material into which it is driven, thus resulting in administering a relatively hard blow to the staple in more effectively driving the staple to its desired tacking relation. The invention has as other salient objects to provide a tacker, that is convenient to load; that is convenient to carry about from place to place; that is of relatively light weight, thus reducing fatigue of the operator; that is smooth in exterior contour, hence preventing tearing or catching of the lining of a pocket of the clothing of the operator; that is relatively narrow in width to allow close positioning of the frame of the tacker adjacent to vertical walls or floor moulding and into corners defined by the latter; that has serviceable means to permit opening of the frame by a single hand of the operator; that has power means to provide instantaneous impact on the part of the driver or ram against the staple and shock absorbing means to allow gradual deceleration of the driver; that has localized stabilizing means of relatively greater mass than the driver, and is sustained by the frame which is hollow and of relatively light sheet metal material which is merely skin stressed during tacking operations; and that has target or indicator means to determine the exhaustion of staples within the magazine even though the latter be closed. Further objects, advantages, and functional and structural features of the invention deal with:— the provision of means to permit convenient withdrawal of the staple driving blade of the reciprocable driver from the staple raceway or guideway upon lifting of the pivoted cover of the tacker from the staple magazine thereof without accidentally lifting the front portion of the staple strip from the magazine, hence preventing accidental spillage of staples out of the magazine in instances where it is desired to open the latter for inspection or loading; and the pro-

vision of novel shiftable supporting means to prevent transverse rocking of the tacker when utilized adjacent the vertical walls or moulding of a room or chamber. Other important objects will be better understood from the teachings of the following detailed description considered in the light of the accompanying drawings wherein:

Fig. 1 is a perspective view of the tacker according to my invention.

Fig. 2 is a perspective view of the tacker, showing the pivoted cover raised and the magazine partly broken away to illustrate the staple follower and the colored target thereon.

Fig. 3 is a longitudinal sectional view of the tacker, illustrating the driver in its normally depressed position, and the actuating handle therefor in a normally raised relation.

Figure 4 is a fragmentary view of Fig. 3 however showing the driver approaching its fully raised position.

Fig. 5 is a view similar to Fig. 4 showing the driver free of the trip pawl and the plunger thereof of moving downwardly towards the fixed abutment or anvil.

Fig. 5^a is a fragmentary sectional view of the pivoted cover illustrating the driver depressed and the control handle returning to its normally raised position.

Fig. 5^b is a fragmentary sectional view of the cover showing the driver leaving the plunger head when the ejecting blade is driving a staple into relatively soft or fluffy material.

Fig. 6 is a sectional view on the line 6—6 of Fig. 3.

Fig. 7 is a sectional view on the line 7—7 of Fig. 3.

Fig. 8 is a sectional view on the line 8—8 of Fig. 3.

Fig. 9 is a transverse sectional view on the line 9—9 of Fig. 3.

Fig. 10 is a fragmentary perspective view of the tacker.

Fig. 10^a is an underneath view of the front part of the magazine.

Fig. 11 is a fragmentary perspective view of the tacker shown partly turned over.

Fig. 11^a is a perspective view of the magazine.

Fig. 12 is a perspective view of the shock absorbing laminated head to reduce recoil of the tacker.

Fig. 12^a is a fragmentary perspective view of the case of the tacker.

Fig. 13 is a fragmentary sectional view of the tacker showing the cover and the magazine in a fully opened relation.

Fig. 14 is a perspective view of the locking retainer for the slidable saddle.

Fig. 15 is a sectional view on the line 15—15 of Fig. 3.

Fig. 16 is a sectional view on the line 16—16 of Fig. 3.

Fig. 17 is a fragmentary view of the tacker showing the latch depressed for unlocking the magazine to permit opening of the pivoted cover.

Fig. 18 is a perspective view of the driver.

Fig. 19 is a sectional view on the line 19—19 of Fig. 6.

Fig. 20 is a perspective view of the latch or trigger, and

Fig. 21 is a fragmentary view of the control arm.

Illustrative of the embodiment disclosed, the tacker T comprises, a magazine 10 and the pivoted cover 11. The magazine is of sheet metal and includes a bottom wall 12, side walls 13, and the front transverse wall 14.

Fixedly sustained within the magazine is the inverted U-shaped rail 15 having a top wall 16 (Fig. 7) disposed below the elevation of the top faces 17 of the magazine sides 13. Depending from the top wall 16 of the rail are the legs or sides 18 which are spaced from side walls 13 of the magazine and define longitudinal gaps 19 for slidably guiding legs 20 of the staples 21 of the staple strip 22 having their crown portions 23 slidably seated on the top wall 16 of the rail.

The inverted U-shaped metal staple follower 24 is slidably guided on the fixed rail and is provided with depending legs 25 (Figs. 2 and 8) having inwardly turned lugs 26 (Figs. 5 and 8) movably disposed in gaps 27 between the sides 18 of the rail and the bottom wall 12 of the magazine. Thus although the follower 24 is slidably guided in the magazine, it is interlocked with the rail.

The forward transverse face 28 (Fig. 4) of the rail 15 is spaced from the inner transverse inner face 29 of the front wall 14 of the magazine thus defining a vertical staple guideway 30. Each side 18 of the rail has at its forward ends spaced depending lugs 31 and 32.

Lugs 31 closely straddle the sides of the square shaped lip 33 of the bottom wall 12 of the magazine and are disposed in the notches 34 and are spaced from inner faces 35 of the sides 13 of the magazine to provide clearing passages 36 for staple chips to permit the latter to fall out of the magazine to prevent clogging. Rear lugs 32 are approximately received and anchored in the locating openings 37 in the bottom wall of the magazine.

It should be understood of course that the rear part of the rail is fixed and suspended within the magazine to sustain the bottom faces 37 (Fig. 5) of the sides of the rail the required distance away from the bottom wall 12 of the magazine to provide gaps 27 to permit free sliding of the lugs 26 of the follower 24 which has a reduced front portion 38 having the front end face 39 adapted to be disposed in alignment with the front transverse face 28 of the rail when shoulders 40 of the follower strike the shoulders 41 defined by the lugs 32. In this way the reduced part 38 of the follower is prevented from projecting into the staple guideway 30 even at times when the latter is exhausted of staples.

Specifically however the rear part of the rail includes a lip 42 (Fig. 13) fixedly positioned in slot 43 in the rear transverse wall 44 of the magazine for sustaining the sides of the rear part of the rail in spaced relation to the inner faces of

the sides and the bottom inside face of the magazine and extending rearwardly of wall 44 are the spaced outside ears 44 (Figs. 1, 9 and 13) of the sides 13 of the magazine. These ears are provided with alined openings or bearings 46 to slidably guide the elongated fulcrum pin 45 transversely of the magazine. These ears 44 also straddle the spaced ears or lugs 47 depending from the sides 48 of the hollow sheet metal case 49 of the cover of the tacker. By this arrangement the case is rotatably or pivotally guided on the fulcrum pin 45 by the outside ears 44 and of course against transverse displacement relative to the magazine, that is, case 49 has its lugs 41 and particularly bearings or guide openings 50 (Fig. 9) thereof rotatably mounted on the elongated shiftable fulcrum pin 45 having its reduced ends 51 secured to the upstanding sides 52 of the one piece saddle or yoke 53 which has a seat 54 movable transversely of the magazine in the alined gaps or cut outs 55 (Fig. 13) in the sides 13. It will be observed that the bottom face of seat 54 is in alinement with the lower face of the bottom wall 12 of the magazine and in fact constitutes a relatively elongated supporting face to prevent transverse tilting or rocking of the tacker when positioned on a work surface.

For locking the balancer or saddle 53 in a neutral position in respect to the magazine, a resilient, flexible and relatively thin sheet metal spring clip or loop denoted 56 (Figs. 9, 13 and 14) is utilized. This clip or retainer comprises hingedly merged curved jaws 57 and 58 defining the gap 59 and common to these jaws and integral therewith is the loop 60. The curved jaws are provided with the locking and alined inwardly projecting detents 61 which snap into gap 62 of the reduced portion 63 of the fulcrum pin 45. This gap 62 is centrally located on the fulcrum pin 45 and its side walls disengageably interlock with or embrace the alined detents when the saddle 53 is slidably shifted transversely of the magazine to its neutral position in which instance sides 52 of the saddle are widely spaced from the sides of the magazine in which case and at all times the clip is prevented from being displaced transversely of the magazine by the inner ears 47 of the pivoted case 49 of the tacker frame.

Where it is desired to use the tacker close to a vertical wall or moulding or get closely into corners, this may be readily accomplished in adjusting the saddle to meet the convenience of the operator. For example, in Figs. 1 and 2, the saddle is in its neutral and locked position and may be readily shifted to appreciably extend beyond the left hand side or to the right hand side of the magazine. For purposes of illustration, the saddle is shown in Fig. 9 appreciably extending beyond the left hand side of the magazine and in the dash and dotted lines as extending appreciably beyond the right side of the magazine. In either extreme position of the saddle the slidably fulcrum pin 45 is freely encompassed by the spaced jaws 57 and 58. In the full line position of the saddle in Fig. 9 the right hand side of the tacker may be placed near a wall or may be placed in corners to get close to the moulding and thus the left part serves as a balancer or stabilizer support to prevent rocking of the tacker when confined in close quarters. Of course the saddle may be reciprocably adjusted to get close to walls or close to corners at either side of the tacker and linear displacement of

the saddle is limited by the outside ears 44 co-operating with the side 52.

Pursuant to desired use of the tacker when the saddle has been shifted to either side thereof to facilitate balancing, the saddle may be quickly reset in its neutral position by shifting the same in the desired direction whereby the fulcrum pin is slidably guided by the aligned bores of the ears 44 and 47 until the locking detents 61 snap into or enter gap 62 about the reduced part 63 of the fulcrum pin. To unlock the retainer from the fulcrum pin, one side as 52 of the saddle is manually forced towards the tacker in which event a side wall of the gap 62 shifts the resilient and separable detents out of gap 62, thus causing at this time the jaws or lips 57 and 58 to be slightly separated but their inherent resiliency or flexibility by reason of the loop restores them to their normal slightly spaced relation when the saddle has been shifted to its neutral position in which case the jaws automatically retract the detents 61 and are interlocked with the side walls of gaps 62.

By the present arrangement the cover C for the magazine is pivotally mounted and consequently the cover may be reciprocably rotated and of course rearwardly relatively to the case until lower margin 65 of the curved top or closure wall 66 of the case 49 of the cover abuts the stop flange 67 (Fig. 13) extending from the base or seat 54 of the reciprocable saddle 53 in which event the cover is approximately one hundred and twenty degrees away from the magazine. Hence the latter at this time is fully opened and complete access is had to the rail and of course to the staple guideway 30.

The cover C embodies the hollow sheet metal case 49 and the U-shaped hollow sheath 70 provided with the front transverse wall 71 having rearwardly extending side walls 72 which closely straddle and embrace the spaced forward portions 73 of spaced sides 48 depending from the wall 66 of the case 49.

The sheath 70 fixedly carries the frame stabilizing or recoil absorbing laminated metal core 74 (Figs. 7 and 12) comprising end plates 75 secured to the juxtapositioned vertically extending and intermediate plates or laminations 76. The outer laminations 75 and the inner laminations 76 are secured together by rivets 77 and 78 flush with the outer laminations.

Since the stabilizing core 74 is utilized to retain and house the upper end of the power spring 80, the outer laminations 75 have their arms 81 extending below the arms 82 of the intermediate laminations 76 which are suitably notched to provide the recess 83 in which the upper part of the power spring 80 is located and retained.

The outer plates 75 of the stabilized core 74 have depending lugs 84 fitting into the locating notches 85 in the front portions 73 of the sides 48 of the case 49. By this arrangement, the core is positively positioned in respect to or interlocked with the case 49. The core is also pivotally located in respect to the sheath 70 by reason of the forwardly projecting and aligned lugs 86 of the intermediate laminations 76 which lugs extend into the positioning slot 87 (Fig. 2) in front transverse wall 71 of the sheath.

In the assembled relation of the case and sheath, the transverse end faces 88 (Figs. 12a and 15) of the front parts 73 of the sides 48 of the case constitute the rear bearing surfaces for the reciprocable and rectangularly shaped staple driver or ram 89 comprising the steel staple eject-

ing blade 90 provided with corner tapered projections 91 (Fig. 18). It should be observed that where the case 49 and sheath 70 are in proper assembled relation the vertical transverse faces 92 (Figs. 4 and 5) of the spaced extensions 93 of the front portions 73 of the spaced sides 48 of the case 49 are spaced from the inner transverse face 94 of the front transverse wall 71 of the sheath 70 to provide a vertical guide gap 95 (Fig. 4) for the staple ejecting blade 90. The gap 95 is in vertical alignment with staple guideway 30 in the magazine. The staple driver however is also movably guided by the vertical guide faces 96 of the laminated core and these guide faces 96 are positioned in alignment with the spaced bearing faces 88 of the case 49 by the locating lugs 84 and notches 85. In fact, faces 88 and 96 constitute the vertically aligned rear bearing faces of the driver guide bore or socket generally denoted 97 (Fig. 15) characterized also by the inner faces 98 of the sides 72 of the sheath and the transverse inner surface 94 of the front wall 71.

Fixedly anchored to the reciprocable hollow driver 89 is the bar 100 which interrupts the elongated bore or well 101 therein. The bottom wall 102 (Figs. 5 and 18) of the driver is provided with an opening 103 for slidably guiding shank 104 of the plunger 105 having the enlarged head 106 normally retained against the seat or bottom wall 102 by the helicoidal normally expanded shock absorbing spring 107 having its lower end continuously abutting the head of the plunger and its upper end abutting the anchored plate 100 which in fact forms a seat for the lower end of the normally expanded helicoidal power accelerating spring 80 disposed in vertical alignment with the shock absorbing spring 107 which is appreciably greater in stiffness than the power or accelerating spring 80. In other words, where a unit load is applied to each of these springs, the deaccelerating spring 107 will have an appreciable less linear deflection than the power spring 80 or more specifically stated, the momentum produced in the driver by the power spring to effect a linear deflection thereof of three quarters of an inch is negated by the shock absorbing spring in undergoing a linear deflection to the extent of one sixteenth of an inch where the driver is idly operated, without any staples or in instances where a staple is driven out of the tacker by the blade into the material and body for example, cardboard and wood or fluffy objects to be tacked together, in such instances while the power spring deflects substantially to the order of three quarters of an inch, the shock absorbing spring undergoes a linear deflection of a few thousandths of an inch only for the material into which the staple is driven absorbs most of the momentum imparted to the driver by the power accelerating spring.

Positioned below the spring controlled plunger 105 and cooperating therewith is the metal anvil or abutment block 110 which closely fits into the aligned openings 111 (Fig. 16) and therefore is supported only by the sides 72 of the sheath. This anvil is provided with a reentrant recess 112 defining lugs 113 closely straddling the spaced shoulders or steps 114 projecting from portions 73 of the sides 48 of the case. In other words, the anvil 110 is interlocked with the case and thus is held against transverse movement relative to the sheath.

Spaced ears 115 (Figs. 1 and 2) extending from sides 72 of sheath 70 closely straddle and embrace the spaced forward portions 73 of the sides

48 of the case and a rivet or fulcrum pin 116 holds ears 115 against the outer faces of the portions 13, the fulcrum pin 116 however pivotally supports and passes through the forwardly projecting and spaced arms 117 of the control lever or handle generally denoted 118 having its manipulating portion 119 extending rearwardly of the sheath.

Associated with the control handle 118 is the pivoted pawl or plunger actuator 120 having a front wall or lip 121 from which rearwardly extends the spaced sides 122 pivoted on fulcrum pin 123 carried by the spaced arms 117 of the control lever 118. These arms 117 also straddle sides 122 of the pawl and their lower faces 124 constitute stop means for the outwardly extending lugs 125 of sides 122 thus limiting counterclockwise rotational displacement of the pawl.

Coiled about fulcrum pin 123 is the spring 126 having one terminal 127 thereof yieldingly abutting the front wall or lip 121 and another terminal 128 appropriately fixedly anchored to an adjacent arm 117 of the control lever. In this way, lip 121 is normally urged in a counterclockwise direction or towards the plunger which includes the reentrant notch 130 for receiving lip 121 and the shoulder 131 adapted to be actuated by lip 121 of the rockable pawl when the manipulating arm 119 is depressed against the resistance of the winged spring 132 having its coiled part 133 surrounding fulcrum rivet 116 and one wing 134 thereof abutting and confined in the arched manipulating arm 119 while its lower wing 135 (Figs. 8 and 15) is confined within the case 49.

More particularly however the lower wing 135 of spring 132 which normally holds the control lever elevated is retained against one of the curved lugs or humps 136 struck out of the pair of juxtaposed reinforcing inserts 137, (Fig. 8), that is, inserts 137 have their collars 138 corresponding in shape to the elongated openings 139 in the spaced sides 48 of the case 49 and the vertical flanges or rims 140 extending outwardly of the collars straddle the spaced sides 48 and are secured thereto by the rivets 141 which extend transversely of the case and hold meeting faces 142 of the collars 138 together. These inserts not only reinforce the case but enhance the appearance thereof and through rivets 141 they are firmly secured to the case of the machine. Humps 136 are utilized in association with flanges 140 to locate and position the respective inserts in the sides of the case which in fact is a hollow and smooth handle reinforced by the inserts, likewise of smooth contour.

According to the invention the pivoted cover C is automatically locked when moved to its fully closed relation with the magazine. For this purpose, a swingable latch or trigger generally designated 145 is utilized. This latch is in the form of a bell crank lever comprising the spaced depending arms 146 and the rearwardly extending manipulating part 147 projecting into opening 148 in the aligned insert 137.

The spaced elbows 149 of the latch 145 are rotatably or pivotally mounted on the fixed fulcrum pin 150 carried by spaced portions 13 of the sides 48 of the case 49. The spaced depending arms 146 of the latch carry the fixed pin 151 on which wheel bearing 152 is freely rotatably mounted and about which the looped end 153 of a normally contracted helicoidal spring 154 is trained. The lower leg or reach 155 of

this spring is provided with an eye 156 through which the arched retaining lug 157 of the follower is threaded and retained. In this way the lower end of the spring is operatively connected to the staple follower block 24.

The upper leg 158 (Figs. 3, 8 and 13) of the looped spring 154 extends rearwardly between the lower parts of the sides 48 of the swingable cover and has an eye 159 connected to hook 160 fastened to one of the sides 48. The spring 154 has several important functions, one being it normally urges to swing latch 145 counterclockwise to its locking or fully retracted position at which time if the cover be closed, overhanging terminals 161 of pin 151, although movably guided in arcuate slots 152' in the spaced portions 13 of the spaced sides 48 and in the registering curved slots 153' in the spaced sides 72 of the sheath, disengageably snap into the aligned but spaced notches 162 in the wings 163 projecting upwardly from the sides 13 of the magazine. Hence in the closed position of the cover terminals 161 which overhang or extend beyond arms 146 interlock with the wings and hold the cover closed.

In the closed relation of the cover and magazine the lower marginal portions 164 (Figs. 3 and 8) of the spaced sides 48 are telescopically received between the sides 13 of the magazine and the wings 163 which extend appreciably above the sides 48 when the cover is closed while the front lower marginal portion 165 of sides 48 of the case extend slightly although telescopically between the sides 13 at the front part of the magazine.

Or stated in another way, marginal portions 165 of the front extension 93 (Fig. 7) of the sides 48 of the case 49 project below the bottom faces 166 of the sides 72 of the sheath 70. Thus in the closed relation of the cover, marginal portions 165 are closely straddled by sides 13 of the magazine or are telescoped in the latter. Marginal portions 164 and 165 thus properly align the cover relative to the magazine.

With the cover closed marginal portions 165 and the marginal portions 164 prevent upward displacement of the staples, facilitating proper sliding thereof towards the raceway 30 and it should be observed that the top faces 17 of the sides 13 of the magazine constitute stop means to limit the extent of the telescopic projection of the case 49 into the magazine when of course the bottom faces 166 of the sheath strikes and becomes seated on the top faces 17 of the magazine.

Referring again to the normally contracted helicoidal spring 154, the lower leg 155 thereof also serves to propel or shift the slidible follower 24 (Fig. 2) away from the raceway 30 when the cover C is swung open. Thus access may be had to the rail for supplying the latter with staples. However in the closed relation of the cover the tension imparted by the leg or reach 155 urges the follower forwardly to project the foremost staple of the staple strip into the raceway 30 and under the staple ejecting blade 90. Briefly recapitulating, it is apparent that the looped spring 154 has at least three important functions; one, it causes terminals 161 of the roller supporting pin 151 to automatically interlock with the wings of the magazine when the cover is completely closed, and thus the cover is held against accidental opening; two, it serves to rearwardly displace the reciprocable follower on the rail when the cover is opened after the

locking terminals 161 have been withdrawn from notches 162 upon manipulation of the tail 147 of the latch 145 downwardly; and three, in the normal closed relation of the cover, it constantly urges the follower forwardly until shoulders 40 (Fig. 5) of the follower strike shoulder 41 of the magazine lugs 32 in which instant of course the magazine is exhausted of staples.

However provision has been made to indicate the approximate or complete exhaust of staples even though the cover be held closed. In this connection, a target or indicator 170 (Fig. 2) has been provided. This target is in the form of a color spot, for example, red, and is painted on one of the side walls of the follower 24. In use, as the target intermittently moves automatically towards raceway 30, during the exhaust of the staples, it will ultimately register with sight opening or perforation 171 in an adjacent side wall of the magazine. This teaches the operator that at least one more staple remains in the magazine and of course the target may be so adjusted as to register the complete exhaust of the staples.

Although marginal portions 164 and 165 of the sides of the case 49 telescope and interlock with the magazine as herein set forth, further means has been provided to supplement the proper positioning of the cover C when the latter is closed. To this end the transverse front wall 71 of the sheath 70 embodies the depending square shaped tongue 172 fitting closely but removably into a correspondingly shaped notch 173 in the front wall 14 of the magazine. With the cover closed the front walls of the sheath and magazine are therefore properly located and held in true vertical and lengthwise alignment as desired.

When the cover is closed, it will be observed (Fig. 3) that the staple strip 22 is urged by the lower leg 155 of spring 154 against the reciprocable staple ejecting blade 90 which in fact closes the raceway 30 in the normal raised position of the handle 118. Thus there is a very slight yieldable frictional engagement of the foremost staple of the staple strip against the back of blade 90. It has been discovered that where it is desired to open the cover pursuant to unlocking latch 145 from the magazine, the blade acts to lift or spill the front part of the staple strip out of the magazine. With the present invention, spillage of staples out of the magazine is prevented by transverse bridge 175 interconnecting and fixedly anchored to the sides 13 at the front part of the magazine. This bridge it has been found resists the front part of the staple strip 22 from tilting out of the magazine when the cover is swung open. The bridge 175 also prevents transverse buckling of the sides of the magazine and constitutes means to properly facilitate positioning and locating of the cover relative to the magazine for the spaced walls 176 (Figs. 3, 11 and 11a) of the spaced notches 177 in the marginal portions 165 of the case 49 closely but removably straddle the long sides of bridge 175 to interlock therewith. In the closed relation of the cover C and the magazine except for the end faces 178 of this bridge the latter is completely concealed and housed by notches 177.

With the sheath 70 mounted on the case 49 and carrying the laminated shock absorbing mass 74, the hinge pins or fulcrum 116 which pivotally supports the control handle 118 may be appropriately upset for holding the sides of the sheath in their desired overlapping relation against the sides of the case. Other rivets 179 and 180 pass through the sides of the sheath 10

and the laminated core 74 to hold the latter together while rivet 181 holds the lower parts of the sides 72 of the sheath against the extensions 93 of the case 49, the rivet 181 carrying the spacing sleeve 182 to prevent buckling or spreading of the sides 48 of the case.

Coming now to the operation of the tacker, the metal frame thereof comprising the magazine, and cover thereof is normally closed. In

10 such relation the handle 118 is in its fully raised position and sides 185 of the hand guard 186 (Fig. 3) are spaced from the rear stop faces 187 of the laminated core 74 and in the fully raised position of the control handle lip 187' thereof is 15 against the stop face 187, although it should be noted that the arms 117 of the control handle 118 straddling the sides 185 of the guard are held thereto by rivet pin 188.

Although the control handle 118 is in its normally raised position, the driver or ram 89 is retracted as shown in Fig. 3, and lip 121 of the pivoted pawl or control actuator 120 is projecting into recess 130 under the shoulder 131. The power spring 80 is in alignment with the shock 20 absorbing stiff spring 107 and shank 104 of the plunger 105 is held against the metal anvil 116 retained by sheath 70. The latch or trigger 145 is also in its normal position in which instant terminals 161 of the locking pin 151 are 25 interlocked in the notches 162 of the wings 163 of the magazine and the reciprocable follower 24 is yieldingly urging the staple strip 22 against the back face of the ejector blade 90 of the ram or driver 89.

30 35 If the control handle 118 be depressed, lip 121 abuts shoulder 131 and the driver is slidably raised. Under these circumstances, the blade 90 moves out of the raceway 30 and the normally expanded power spring 80 is compressed.

40 Thereafter the follower shifts the staple strip 22 and the foremost staple thereof is arranged in alignment with the raceway 30 and below the blade of the driver.

45 As the handle 118 is swung downwardly against the resistance of the spring arm 134, lip 121 ultimately clears (Fig. 4) shoulder 131 when the plunger reaches the complete up stroke. The power spring now instantly expands and the driver retracts or returns (Fig. 5), thus moving 50 the slidably guided blade downwardly to eject the staple through the guideway 30 and ultimately the slidably guided shank 104 of the plunger 105 strikes the locked abutment or anvil (Fig. 5a) 110.

55 Although the pawl has tripped the driver it still is moving upwardly until arms 117 of the control handle meet the inclined stop faces 188 of the laminated core (Fig. 5). The power accelerator spring 80 discharges its energy and causes the driver to be automatically retracted

60 or returned and hence the blade drives the foremost staple of the staple strip out of the guideway 30 and into the material to be tacked at the instant the crown of the driven staple reaches the material, the yieldable plunger 105 impacts the anvil.

65 As this occurs there is a tendency for the frame of the tacker to recoil or rebound, thus materially reducing the intensity of the driving blow on the staple. By the present invention the recoil is materially and appreciably reduced by

70 reason of the heavy laminated mass 74 situated above the driver in that the reacting force or recoil is transmitted to the driver through the blade, from the driver to the power spring 80, and ultimately to the shock or recoil absorbing mass or core 74. Moreover the reacting effect of the im-

pact applied by the plunger 105 on the anvil 110 retained in the side walls 72 of the sheath 70, is absorbed by the shock absorbing spring 107 which in fact acts as a resilient cushion and at no time during the operation of a downward blow on the part of the driver does the bottom wall 102 thereof strike the anvil 110, thus while the sheath becomes skin stressed, such stress is materially reduced and hence fracture of the sheath is precluded for the plunger of the driver strikes the sheath directly and the driver never strikes the steel anvil directly.

Pursuant to the tacking operation the control handle 118 is still held depressed by the operator and on the removal of the hand pressure thereon, this handle revolves counterclockwise, (note arrow in Fig. 5a) at which time lip 121 is yieldingly abutting the driver, being tipped slightly against the resisting action of arm 127 of the spring 126, thus lugs 125 (Figs. 5a and 21) are away from the stop faces 124 of the arms 117. By this construction it is possible for pawl 120 to move automatically into notch 130 when the control arm 119 is raised.

Where the tacker is idly operated or where it is used to tack into soft material, in the first instance there is no resisting medium offered to the ejection of the staples, and in the second instance the resistance is not great. In either of these instances the impact on the anvil on the part of the plunger is fairly great. But this intense impact is absorbed by the shock absorbing spring 107 (Fig. 5a) which becomes compressed as head 106 of the plunger leaves its seat 102 and of course pursuant to the ejection of the staple, spring 107 instantly expands and the driver is automatically restored to its normal position in which instant the head of the plunger is again against seat 102.

By the present invention it is apparent that where a relatively great, concentrated or localized mass is positioned over the driver the recoil of the frame of the tacker is materially reduced, and consequently relatively less mass is required for the remaining parts of the tacker, therefore the latter merely comprises relatively light weight hollow members, for example, the sheath, case, and magazine, the components forming the frame of the tacker are merely of sheet metal stamped into channeled shaped forms, the sheath merely taking incidental internal stresses following driver impacts.

By reason of the fact that the frame of the tacker is hollow throughout and a concentrated mass is positioned above the driver, the weight of the tacker herein disclosed is appreciably light. Therefore in actual practice the tacker according to the invention reduces fatigue in the matter of operating and thus may be readily handled with a maximum of ease and convenience. Since also the internal stresses are merely transmitted to the sheath, the remaining parts of the cover and the magazine are not materially stressed, thus preventing these parts of the frame from getting out of relative alignment, thus precluding incidental buckling or breakage thereof, salient characteristics and advantages resulting by reason of the relatively heavy shock absorbing laminated mass over the driver which mass is relatively greater than the mass of the driver.

Where access is desired to the rail, the operator merely depresses manipulator 147 causing latch 145 to be tilted, thus removing the free ends or terminals 161 of the pintle or pin 151 from the aligned notches 162 of the wings 163 of the sides 13 of the magazine. Thereafter

the cover of the tacker characterized by the case and sheath thereof may be swung rearwardly (Fig. 2) until limited by the stop 67 and thus access is had to the staple rail. To close the cover, the latter is swung downwardly against the magazine whereby the free ends 161 of pintle 151, ride on cam surfaces 200 of the wings 163 until reaching notches 162 at which time spring 154 automatically shifts the roller 152 rearwardly and therefore the free ends 161 of the pin 151 become interlocked with the walls of notches 162. The tacker is now in its normally closed and locked relation and the swingable cover is prevented from accidental opening.

Thus it is apparent that a relatively light weight tacker is provided wherein stabilizing means over the driver is utilized to absorb the frame recoil and wherein the acceleration of the driver is retarded by a reciprocable shock absorbing plunger cushioned by a relatively stiff spring in axial alignment with a lighter power accelerator spring. These functional and structural features constitute important aspects and advantages of the invention in the matter of providing a relatively light weight tacker adapted to be conveniently operated and controlled. As a further aspect of the invention, the tacker herein specifically set out may be idly operated when empty of staples without causing fracture 20 of the frame even though an intense impact is administered by the plunger of the driver to the abutment block or anvil 110 at the time the tacker is empty or even when staples are driven through soft or fluffy material. These and other 30 advantages are inherent in the herein disclosed tacker.

Furthermore it should be realized that with the tacker according to the invention, the frame thereof is of relatively thin sheet metal stock so that the overall width of the machine is only slightly greater than the width of the staple strip, hence permitting the tacker to be placed in narrow and ordinarily inaccessible corners and also permitting staples to be driven therefrom even though the tacker be disposed contiguous to a wall or a corner and balanced and supported against transverse rocking when so disposed in difficult positions for the operator.

By the present invention it is apparent that the relative light weight but stabilized staple tacker herein disclosed also embodies automatic staple follower action in the matter of closing or opening of the cover and providing complete inside accessibility to the staples in the staple raceway or guideway in the magazine at a time when the cover is swung rearwardly of the magazine at which time the latter may be conveniently loaded with staples even though the operator is in awkward positions, for example, such as on a step ladder, scaffold or the like. For reasons expounded in the foregoing detailed and complete disclosure, the successfully operating and most serviceable tacker according to the invention is now offered to the existing and contemporary stapling art.

As many changes could be made in the above described construction and many widely different species or structural embodiments could be devised without departing from the scope thereof, it is intended that all matter hereinbefore described in the specification and illustrated in the accompanying drawings shall be interpreted as illustrative and not in a limiting sense.

I claim:

1. In combination, a staple magazine having

spaced sides, a pin disposed transversely across said magazine and slidably sustained by said sides and having ends adapted to project laterally of said sides, a channeled shaped saddle slidably guided transversely of said sides and having spaced arms secured to said ends for movably straddling said sides, and spring means including detent means for disconnectably interlocking with said pin to prevent displacement of said saddle transversely of said magazine.

2. In combination, a staple magazine having spaced sides, a pin disposed transversely across said magazine and slidably sustained by said sides and having ends adapted to project laterally of said sides and including a reduced portion intermediate said sides and defining therewith spaced shoulders, a channeled shaped saddle slidably guided transversely of said sides and having spaced arms secured to said ends for movably straddling said sides, and spring means comprising spaced jaws including detent means adapted to be arranged within said reduced portion and cooperating with said shoulders for disconnectably interlocking with said pin to prevent displacement of said saddle transversely of said magazine.

3. In combination, a staple magazine having spaced sides, a pin disposed transversely across said magazine and slidably sustained by said sides and having ends adapted to project laterally of said sides, a channeled shaped saddle slidably guided transversely of said sides and having spaced upstanding arms secured to said ends for movably straddling said sides, and spring means disposed intermediate said sides and sustained by said pin and including detent means for disconnectably interlocking with said pin to prevent displacement of said saddle transversely of said magazine.

4. In combination, a staple magazine having a bottom wall and spaced sides, a pin disposed transversely across said magazine and slidably sustained by said sides and having ends adapted to project outwardly and laterally of said sides and including spaced stop means, a channeled shaped saddle slidably guided transversely of said sides and having spaced arms secured to said ends for movably straddling said sides and including a bottom seat integral with said arms and in alinement with said wall, and spring means comprising spaced jaws including detent means disconnectably interposed between said stop means to prevent displacement of said saddle transversely of said magazine.

5. In combination, a staple magazine having spaced sides, a pin disposed transversely across said magazine and slidably sustained by said sides and having ends adapted to project laterally of said sides and including a contracted portion, a channeled shaped saddle slidably guided transversely of said sides and having spaced arms secured to said ends for movably straddling said sides, and loop spring means comprising jaws normally held widely spaced apart by said pin and including detent means disconnectably engageable with said contracted portion upon automatic movement of said jaws towards each other to prevent displacement of said saddle transversely of said magazine.

6. In combination, a staple magazine having spaced sides, a pin disposed transversely across said magazine and slidably sustained by said sides and having ends adapted to project laterally of said sides, a channeled shaped saddle slidably guided transversely of said sides and having

spaced arms secured to said ends for movably straddling said sides, spring means comprising spaced jaws including detent means for disconnectably interlocking with said pin to prevent displacement of said saddle transversely of said magazine, a cover swingably mounted on said pin and adapted to be swung towards or away from said magazine to close or open the latter, and stop means carried by said saddle and cooperating with said magazine to limit the extent of movement of said cover rearwardly away from said magazine.

7. In combination, a staple magazine having spaced sides, a pin disposed transversely across said magazine and slidably sustained by said sides and having ends adapted to project laterally of said sides and including a groove interposed between said sides, a channeled shaped saddle slidably guided transversely of said sides and having spaced arms secured to said ends for movably straddling said sides and including a bottom seat interconnecting said arms, spring means sustained solely by said pin and including detent means for disconnectably interlocking with the walls of said groove to prevent displacement of said saddle transversely of said magazine, a cover swingably mounted on said pin and adapted to be swung towards or away from said magazine to close or open the latter, and a lip extending from said saddle and cooperating with the rear of said cover to limit the extent of movement of the latter rearwardly away from said magazine.

8. In combination, a staple magazine having spaced sides, a pin disposed transversely across said magazine and slidably sustained by said sides and having ends adapted to project laterally of said sides, a channeled shaped saddle slidably guided transversely of said sides and having spaced arms secured to said ends for movably straddling said sides, an expandible and contractible loop spring comprising spaced arcuate jaws including detent means for disconnectably interlocking with said pin to prevent displacement of said saddle transversely of said magazine, a cover swingably mounted on said pin and adapted to be swung towards or away from said magazine to close or open the latter, a staple supporting rail within said magazine, a follower slidably mounted on said rail, spring means interconnecting said follower and cover for shifting said follower rearwardly of said rail upon opening of said cover and for shifting said follower towards the front of said rail upon closing of said cover, driving means to expel a staple from said magazine, said follower having color indicator means, and one of said sides of said magazine having an opening for registering said indicator means.

9. As a new article of manufacture, a slidable saddle having upstanding arms, pin means connected to said arms and having a grooved portion, a support slidably carrying said pin means, and a spring clip comprising arcuate jaws encompassing said pin means and having detent means adapted to removably snap into said grooved portion to prevent displacement of said saddle relative to said support.

10. In a stapling machine, a staple magazine, a pin projecting laterally of and disposed transversely of said magazine and slidably sustained thereby, a stabilizing saddle having upstanding arms secured to said pin and straddling said magazine, and disengageable locking means to prevent displacement of said saddle relative to said magazine comprising a spring clip mounted

on said pin and including detent means and a grooved portion in said pin for removably interlocking with said detent means.

11. In a stapling machine, a staple magazine, a pin projecting laterally of and disposed transversely of said magazine and slidably sustained thereby, a substantially U-shaped stabilizing saddle having upstanding arms secured to said pin and adapted to widely straddle said magazine, disengageable locking means to prevent displace-

ment of said saddle transversely of said magazine comprising a spring clip mounted on said pin and including detent means and a grooved portion in said pin for removably interlocking with said detent means, said magazine embodying a bottom wall, and said saddle having a bottom wall substantially in horizontal alignment with the bottom wall of said magazine.
